(57) **CLAIM**

The ornamental design for a glass fishing tackle, as shown and described.

DESCRIPTION

FIG. 1 is a perspective view of one embodiment of a glass fishing tackle with a fish hook and eyes.

FIG. 2 is a right side view thereof, the left side view being a mirror image of the right side.

FIG. 3 is a top view thereof.

FIG. 4 is a bottom view thereof.

FIG. 5 is a rear view thereof.

FIG. 6 is a front view thereof.

FIG. 7 is a right side view of an embodiment of a glass fishing tackle with a fish hook and a weed guard.

FIG. 8 is a left side view of an embodiment of a glass fishing tackle with a fish hook and a spoon.

FIG. 9 is a right side view of a second embodiment of a glass fishing tackle with a fish hook, the left side view being a mirror image of the right side.

FIG. 10 is a top view of the fishing tackle of FIG. 9.

FIG. 11 is a bottom view of the glass fishing tackle of FIG. 9.

FIG. 12 is a rear view of the glass fishing tackle of FIG. 9.

FIG. 13 is a front view of the glass fishing tackle of FIG. 9.

FIG. 14 is a right side view the glass fishing tackle of FIG. 9 with a fish hook extending upwards from the top.

FIG. 15 is a perspective view of a glass third embodiment of a glass fishing tackle with a fish hook.

FIG. 16 is a right side view of the glass fishing tackle of FIG. 15, the left side view being a mirror image of the right side.

FIG. 17 is a top view of the glass fishing tackle of FIG. 15.

FIG. 18 is a bottom view of the glass fishing tackle of FIG. 15. FIG. 19 is a rear view of the glass fishing tackle of FIG. 15; and,

FIG. 20 is a front view of the glass fishing tackle of FIG. 15. The broken lines are for illustrative purposes only and form no part of the claimed design.
